UNITED STATES PATENT OFFICE.

SIDNEY GEORGE BROWN, OF LONDON, ENGLAND.

COMPENSATING DEVICE FOR TELEPHONIC CIRCUITS.

1,140,946.

Specification of Letters Patent.

Patented May 25, 1915.

Application filed September 19, 1912. Serial No. 721,282.

To all whom it may concern:

Be it known that I, SIDNEY GEORGE BROWN, a subject of the King of Great Britain, residing at 4 Great Winchester street, in the city and county of London, England, have invented certain new and useful Improvements in Compensating Devices for Telephonic Circuits, of which the following is a specification.

10 This invention relates to a compensating device to be used in telephonic circuits for the purpose of preventing sounds which enter the transmitter from appreciably affecting the receiver at the same end of the line, 15 the device providing the desired compensating effect without substantial loss of current or interference with the messages received from the other end of the line.

According to my invention I shunt the 20 transmitter with a compensating coil so adjusted with relation to a coil of the adjacent receiver or telephonic relay as to annul the inductive effect upon the receiver or relay of changes of current due to the said trans- 25 mitter.

The compensating coil is especially useful with telephonic relays, where disturbing sounds are liable to be greatly magnified, but it is also serviceable in ordinary and in 30 long distance telephonic work. It may, where necessary, be provided with adjustable resistance, capacity and self induction to permit of more perfect compensation.

Telephonic relays may be arranged to 35 work in the center of a line with but little loss of efficiency, by placing the primary of the receiving transformer in series with the secondary of the sending transformer, and compensating the effect of the latter on 40 the former by means of the compensating coil.

In order that the said invention may be clearly understood and readily carried into effect, I will describe the same more fully 45 with reference to the accompanying drawings, in which:

Figure 1 is a diagram showing the application of my compensating coil to a telephone employing a telephonic relay. Figs. 50 2 and 3 are diagrams showing the application of the compensating coil to another type of connection. Fig. 4 is a diagram showing the coil applied to a telephonic relay in the middle of a long distance circuit, and Fig. 5

shows the invention applied to a double relay.

A is the telephone circuit line.

B is the transmitter.

C is the receiver.

D is the compensating coil the circuit d^* 60 of which is connected across the transmitter.

Referring to Fig. 1 it will be seen that any disturbances due to the transmitter B causes a change of current through the coil c which if not compensated would set up 65 a current in the secondary receiver coil c' . The compensating shunt coil D however is wound and connected across the transmitter B so as to act in opposition to the change of current passing through the coil c and to 70 neutralize its effect upon the secondary receiver coil c' . The coil D takes only a small fraction of the total current and consists of a large number of turns of fine wire so that the currents flowing through it produce 75 equal and opposite effects to the currents simultaneously flowing through the coil c , so far as disturbances arising from the shunted transmitter B are concerned. The compensating circuit may include an ad- 80 justable capacity d and inductive resistance d' to permit of more perfect compensation. The capacity d may be provided with a high resistance shunt d^2 . The receiver C is shown with a relay c^2 , used for long distance te- 85 lephony, when the compensating coil proves of special advantage owing to the great magnification of the sounds due to the relay.

Fig. 2 shows the application of the compensating coil to the Western Standard connection, in which an auto-transformer c^* is placed in the circuit A, this auto-transformer serving in place of the two transformer coils c and c' in the connections previously described. The circuit A also in- 95 cludes a condenser a and the transmitter B is connected across the receiver C, the condenser a and part of the auto-transformer c^* . The compensating coil D is placed at the auto-transformer to annul the inductive effect upon the transformer, and hence 100 upon the receiver, of disturbances from the transmitter.

In Fig. 3 the same type of connection is employed as in Fig. 2, but instead of compensating at the auto-transformer the receiver is shunted by a coil c^3 and the compensating coil D acts upon this receiver 105

shunt coil. The compensating coil in this arrangement causes the current oscillations due to the adjacent transmitter to be practically confined to the shunt coil c^3 and to leave the receiver almost unaffected, while for distant impulses only a small fraction is shunted by the coil c^3 and the action of the receiver is not appreciably interfered with.

In the arrangement illustrated in Fig. 4 10 the coil D is applied to a telephonic relay in the middle of a long distance circuit, the coil being connected across the sending on transmitter B, which is under the control of the receiving transformer c, c' through the 15 relay c^2 . The arrangement is substantially the same as that already described in connection with Fig. 1, excepting that the transmitter B replaces the receiver C in the relay circuit. Disturbances due to the action of 20 the sending on transmitter, which affect the receiver coil c at the same time causing compensating impulses in the coil D so that the receiving transformer circuit is unaffected.

The double relay of Fig. 5 does not differ 25 in its action from the relay already described, but is connected across the two line wires A. It therefore comprises two sending on transmitters B and receiving transformers c, c' and two compensating coils 30 connected across the sending on transmitters.

In each case where a transmitting coil is used, the compensating coil may, if preferred, be connected across only a portion of the transmitting coil instead of shunting the 35 transmitter as a whole.

What I claim and desire to secure by Letters Patent of the United States is:—

1. In a telephonic circuit, a microphonic transmitting element, a receiving element 40 adjacent to the transmitter and a compensating coil at the receiving element connected in shunt to the transmitting element and so wound as to annul the inductive ef-

fect of the latter upon the said receiving element.

2. In a telephonic circuit, a microphonic transmitting element, a receiving element adjacent to the transmitter, a transformer for the said receiving element and a compensating coil at the receiving element, connected in shunt to the transmitting element and so wound as to annul the inductive effect of the latter upon the said receiving element.

3. In a telephonic circuit, a microphonic transmitting element, a receiving element adjacent to the transmitter, a compensating coil at the receiving element connected in shunt to the transmitting element, and adjustable capacity and resistance in the circuit of the compensating coil.

4. In a telephonic circuit, a microphonic transmitting element, a receiving element adjacent to the transmitting element, a compensating coil at the receiving element connected in shunt to the transmitting element, and adjustable capacity, self induction and resistance in the circuit of the compensating coil.

5. In a telephonic circuit, a microphonic transmitting element, a receiving element adjacent to the transmitter, a telephonic relay operated by a sending on receiving element and controlling the said transmitting element and a compensating coil at the receiving element, connected in shunt to the transmitting element and so wound as to annul the inductive effect of the latter upon the said receiving element.

In testimony whereof I affix my signature in presence of two witnesses.

SIDNEY GEORGE BROWN.
